CARBON PAPER AND ITS HOLDER

William J. Feitl, Chicago, Ill.

Application May 12, 1944, Serial No. 535,219

4 Claims. (Cl. 282—19)

The present invention pertains to certain features of betterment and advancement in pigmented-sheets, such as carbon-paper sheets, and their holders employed in typewriting a plurality of copies at the same time.

The making of a number of copies on a typewriter simultaneously is well known by the use of a corresponding plurality of sheets of carbon-paper interposed between the layers of paper being written upon and this invention is directed to certain improvements in the carbon-paper sheets so availed of and in their holders, as for example, those brought into play between the layers of a fan-folded paper-supply sheet transversely perforated at intervals so that after having been typewritten upon a section can be torn off of the supply and then torn lengthwise at the folds to provide the number of individual copies.

One outstanding object of the invention is to reduce the expense of supply of such carbon-paper sheets and to lessen the cost of using such sheets, by diminishing the portions of sheets which must unavoidably be wasted by non-use during their employment.

Another aim of the invention is to make such savings possible while at the same time evading complexity in the means employed, avoiding difficulty in the use of the new structure, and rendering replacements expeditiously possible, etc.

To enable those acquainted with this art to understand the invention both from structural and functional standpoints, a present preferred embodiment of the invention in physical form has been illustrated in the accompanying drawing forming a part of this specification and to which reference should be had in connection with the following detailed description, like reference numerals having been employed in the several views of the drawing to designate the same parts of the construction.

In this drawing—

Figure 1 is a perspective view of the novel holder of the carbon-paper with which it is loaded;

Figure 2 shows the holder opened up and the folded carbon-sheet partially expanded to illustrate its plaited construction;

Figure 3 portrays a portion of the carbon-paper sheet extended out of the holder for use between contiguous layers of the fan-folded paper to be typewritten upon;

Figure 4 depicts somewhat diagrammatically the long, folded, supply sheet to be typewritten upon, the intervening carbon-paper holders in dotted lines, and the mechanical means cooperating therewith; and

Figure 5 is an enlarged cross-section on line 5—5 of Figure 4.

By reference to the drawing, it will be noted that each simple, novel and improved carbon-paper holder, of which there would be one less than the number of layers of the blank, fan-folded supply-sheet, comprises a rectangular sheet of pasteboard or comparable material folded transversely at right-angles to its length at 12 and 13 to provide at one end a relatively narrow, pocket strip or holding-flap 14, and at the other end a comparatively long cover flap 15 of a length to have a small end portion thereof accommodated beneath the holding-flap 14, the intervening, rectangular, main body or back of the holder being designated 16.

Contained in this simple folded holder is a long, continuous sheet of carbon-paper 17 of approximately the same width as the holder, and folded crosswise at equal intervals apart at 18, 18 to provide a plaited sheet all plies of which are of the same length and slightly shorter than the back 16 of the pasteboard holder.

The pigmented face of such folded sheet is the top surface of the top, 3rd, 5th, 7th, etc., ply and the under surfaces of the remaining alternate plies.

When the holder is originally sold loaded with one of the plaited carbon-paper sheets, the forward edge of such folded, pigmented sheet is beneath the holding-flap 14 and approximately at the fold 12 and the cover-flap 15 overlies the folded sheet 17 and the end portion of the cover-flap is also beneath the holding-flap 14, but above the carbon-paper, and these removable parts are thus held assembled by a spring-metal clip 19 underlying the back 16 and overlying the holding-flap 14.

To get this combination ready for use between two plies of the longitudinally folded, paper-supply sheet to be typewritten upon, clip 19 is removed, the cover-flap 15 lifted and a suitable length of the carbon-paper 17 lifted and advanced out of the holder as shown in Figure 3, then the cover-flap 15 is replaced beneath the holding-flap 14 beneath that portion of the then top layer of the carbon-paper still remaining beneath the flap, but on top of the next full layer, and then the clip or clamp is replaced as shown in Figure 3.

In manifolding work of this kind, the typewriter-carriage (not shown) has movable with it a support equipped with a forwardly and rearwardly movable carrier on which the several car-

bon-paper sheets are mounted, but inasmuch as this is an old and well known structure and mode of operation, it has not been shown in detail and so much only thereof as is new is presented, a portion of such carrier being designated 22 in Figures 4 and 5.

At opposite sides of the paper-supply strip 21, such carrier has hinge pins 23, 23 on which are rockingly mounted flat, vertically-spaced arms 24, 24 extended inwardly in opposite directions between the plies of the fan-folded sheet 21, each such arm occupying the space in one of the carbon-paper loaded holders between the fold 13 and the adjacent folded edges 18 of the carbon-paper.

Each hinged arm 24 is apertured to receive a locking-pin 25 whose lower end demountably occupies a corresponding hole in the base 26 of the carrier 22.

Obviously, when either of the two pins 25 is lifted out, all of the arms 24 of that group are released or unlocked and may be swung out individually from the folded paper-sheet 21 as illustrated in dotted lines in Figure 4 and the corresponding carbon-paper and its holder mounted thereon as specified, whereupon the arm is rocked back into place with the holder and its carbon-paper between the corresponding layers of the paper 21 ready for service of that portion of the carbon-paper extended forwardly out of its holder.

When all such arms of that group have received their carbon-paper, the arms are locked against turning by their common pin 25 until replacement of carbon-paper is required.

As is well understood in the art, during the typewriting of such paper 21 by means of the typewriter-ribbon and the interleaved sheets of carbon-paper, both the paper and the carbon sheets advance step by step as the typewriter-platen is turned intermittently and when that portion of the multi-layer strip 21 has been completed, the platen is released, the carriage 22 recedes to the dotted line position shown in Figure 5 carrying the carbon-sheets and their holders with it, and the typewritten layers of sheet 21 are torn off and the operation then repeated.

Of course, in time the exposed or extended portions of the carbon-papers become worn out, and the used up portions only of the carbon-papers are torn or cut off and replaced by like lengths from the supplies in the holders, and when such new sections of the carbon-papers are of no further use, they are replaced in like manner.

Each folded carbon-sheet is ordinarily several feet in total length which will give satisfactory service for some time as will be apparent, and each time that a depleted section is cut or torn off there is no waste of any unused section of the paper.

When, however, the last part of the pigmented-paper is of no further use, there is a slight length of the final end of the paper which is unavailable,

but such loss is negligible as compared with the heavy losses by reason of waste incident to the employment of the present means and systems now available.

5 When new holders and their carbon-papers are needed the arms 24 are unlocked and swung out whereupon the old holders can be readily removed and replaced by new loaded ones, and then the arms are rocked back into place and

10 locked therein.

When new supplies of carbon-paper are required it is not always necessary to supply them in new holders, since the ones already in use can continue in service over a considerable period of time, and hence only the transversely folded or plaited carbon-paper need be purchased without the added expense of holders each time.

15 This invention as defined hereinafter is not necessarily limited and restricted to the precise and exact details of structure set forth and these may be modified within reasonable limits without departure from the heart and essence of the invention and without the loss or sacrifice 20 of any of its substantial benefits and advantages.

For example, one purpose of the cover-flap 15 is to overlie the folded carbon-paper sheet and thereby protect it from injury or displacement, but it need not necessarily be of a length to 30 extend beneath the holding or clamping flap 14.

I claim:

1. In a pigmented-sheet construction incorporating a holder and a folded pigmented-sheet in said holder, the novel improvements being 35 that said holder includes a back, a holding-flap overlying the front of, and hinged to, one end of said back, a cover-flap overlying the front of said back and hinged to the opposite end thereof, a continuous pigmented-sheet at least in part 40 beneath said cover-flap and folded crosswise into plaited form, one end portion of such plaited pigmented-sheet being between said holding-flap and said back, and a clamp overlying said holding-flap and underlying said back releasably 45 maintaining said plaited pigmented-sheet in the specified relation, whereby a section of said plaited pigmented-sheet may be released from beneath said holding-flap and occupy an advanced operative position, the remainder of 50 the plaited-sheet being held clamped beneath said holding-flap.

2. The novel improvements set forth in claim 1 in which said cover-flap is of a length to have a portion of it clamped beneath said holding-flap.

3. The novel improvements set forth in claim 1 including the additional novel improvement that there is a space between the hinge of said cover-flap and the adjacent folds of said plaited pigmented-sheet.

4. The novel improvements set forth in claim 1 in which said flaps are integral with the back of said holder.

WILLIAM J. FEITL.
